M. B. LLOYD

EDGE BINDER AND METHOD OF PRODUCING THE SAME

Filed Sept. 16, 1921

FIG. 1.

FIG. 2.

FIG. 5.

FIG. 7.

FIG. 3.

FIG. 4.

Inventor:

Marshall B. Lloyd
by *Arthur W. Wilson*
Atty.

UNITED STATES PATENT OFFICE.

MARSHALL B. LLOYD, OF MENOMINEE, MICHIGAN, ASSIGNOR, BY MESNE ASSIGNMENTS, TO LEVI H. GREENWOOD AND GEORGE A. KEYWORTH, BOTH OF GARDNER, MASSACHUSETTS, AND WILLIAM E. HOLMAN, OF LEOMINSTER, MASSACHUSETTS, TRUSTEES.

EDGE BINDER AND METHOD OF PRODUCING THE SAME.

Application filed September 16, 1921. Serial No. 501,210.

To all whom it may concern:

Be it known that I, MARSHALL B. LLOYD, a citizen of the United States, and a resident of Menominee, county of Menominee, and 5 State of Michigan, have invented a certain new, useful, and Improved Edge Binder and Method of Producing the Same, of which the following is a specification.

My invention relates generally to methods and means for binding the strands forming an edge of a fabric, but relates more particularly to the binding of woven reed fabric and the like.

The general object of my invention is to 15 provide a method of binding or securing the edge of such a fabric in a simple, quick and easy manner. It is also an object of my invention to provide an edge binder and method which shall securely lock the strands 20 against displacement and in such manner that it will withstand great pulling or tensile forces.

I aim also to provide an edge binder and a method of applying the same whereby the 25 binder strip shall be wrapped by or within the strands which it secures.

My invention consists generally in an edge binder, and method of application thereof, whereby the above named objects, 30 together with others that will appear hereinafter, are attainable; and my invention will be more readily understood by reference to the accompanying drawings, which illustrate what I consider, at the present time, to 35 be the preferred embodiment thereof.

In said drawings:

Fig. 1 is a face view of a piece of woven reed or like fabric, the edges of which are to be bound.

40 Fig. 2 is a face view of a metal strip used for the binder.

Fig. 3 illustrates one step in the process of preparing the metal strip for application to the fabric.

45 Fig. 4 shows the metal strip of Fig. 3 in position in the fabric, preparatory to the interlocking operation.

Fig. 5 shows a further step in forming the interlock.

50 Fig. 6 is a view of a piece of fabric completely locked; and

Fig. 7 is an enlarged sectional view substantially on the line 7—7 of Fig. 6.

The fabric here shown is typical of woven reed fabric and the like and embodies there- 55 in a plurality of stakes 1, over and under which filler strands 2 are woven. Under methods of manufacture devised by applicant and heretofore patented, it is now the practice to weave the reed fabric and the 60 like independent of the frame, of which it is to form a part, and thereafter to attach it to the frame. In order that the fabric may be manipulated without danger of the stakes or strands becoming loose or displaced, and 65 also as an aid in applying the fabric to the frame it is necessary, or at least highly desirable, to bind or secure the ends of the 70 filler strands.

Sheet metal, such as brass or steel, is gen- 70 erally employed for this purpose. The tex- 75 ture of metal and that of the reed fabric is quite different and when the metal is placed around the strands, i. e. the strands placed within a channel of metal, the metal is com- 80 pletely exposed to view and detracts from the appearance of the fabric. Reed fabric, especially if it is the natural reed, is some- 85 what brittle and special care must be taken to prevent the sharp edges of the metal en- 90 gaging and cutting the fabric. At the same time, it is necessary firmly to bind the edge of the fabric since it is often used in articles of furniture where considerable pulling or 95 tensioning of the strands occur, and such as 85 would withdraw them unless very tightly held.

I have devised an edge binder and a 90 method of applying the same, which tena- 95 ciously holds the strands in place; which presents no sharp edges such as can injure the fabric and which, at the same time, is partially hidden from view, thus removing the objection that inheres in a metallically 95 bound fabric of reed and the like when the edge binder is completely disclosed to view.

Having provided the woven reed or like fabric, as shown in Fig. 1, I next provide a strip or ribbon of metal of the proper length, as shown in Fig. 2. As a next step, 100 the ribbon of metal 3 is pressed or shaped to the form shown in Fig. 3, i. e. substantially V-shaped, having a curved bottom portion 3'. Alternate filler strands 2 are bent in op- 105 posite directions from the central plane of the fabric and the metallic member in the

2
form shown in Fig. 3 is inserted as indicated in Fig. 4. In order to prevent the distortion of the V-shaped metal member and particularly to maintain the round bottom portion thereof, I temporarily insert a metal rod 4 which remains in place during the subsequent forming operations and is thereafter removed.

Having thus positioned the parts, as shown in Fig. 4, as a next step the V-shaped metal and the contiguous filler strands are bent partially inward, as indicated by the dotted line portion in Fig. 4. As a matter of convenience in performing these operations, the fabric is usually clamped in place, as by means of a screw clamp 5 illustrated in Fig. 5. As a next operation a die 6 forces the end portions of the V-shaped metal strip and the encompassing filler strands downwardly to the position shown in Fig. 5, lateral displacement of the parts being limited by the spacing bars 7 and 8 respectively. The die 6 is then removed and the temporary rod 4 withdrawn, after which side pressure is applied to compact or close the parts to the form shown in Figs. 6 and 7. By referring to Figs. 6 and 7, it will be observed that the respective filler strands pass completely around the outer portions of the metal binder and then pass downwardly between those portions of the metal binder strip that were initially inwardly formed. It should, furthermore, be observed that all edge portions of the metallic binder that contact the filler strands are curved or rounded, thus obviating any danger of cutting or injuring the strands.

Any pulling or tensioning forces that are applied to the strands do not directly tend to pull the strands from their position within the binder strip, since they are first "snubbed" by the wrapping thereof around the curved portions, before referred to. The result is that a strong, light, and extremely durable fabric is provided which can be manipulated and used without danger of disintegration.

Again since the strands pass over the outer surface of the metallic binder the continuous smooth or flat appearance thereof is destroyed and an appearance better adapted to harmonize with the fabric is produced.

The many advantages of this construction will occur to those skilled in this art, without further comment.

I claim:

1. The method of binding the edges of reed fabric and the like that consists in providing a strip of binding material substantially V-shaped in cross-section, in separating the strands to be bound, placing the V-shaped strip between the separated strands, and forming the strands and the upper portions of the V-shaped binder strip inwardly.

2. The method of binding the edges of reed fabric and the like that consists in providing a strip of binding material substantially V-shaped in cross-section, in separating the strands to be bound, placing the V-shaped strip between the separated strands, forming the strands and the upper portions of the V-shaped binder strip inwardly, and then pressing the parts into compact relation. 70

3. The method of binding the edges of reed fabric and the like that consists in providing a strip of binding material substantially V-shaped in cross-section, but with a curved bottom portion, in separating the strands to be bound, placing the V-shaped strip between the separated strands, and forming the strands and the upper portions of the V-shaped binder strip inwardly. 80

4. The method of binding the edges of reed fabric and the like that consists in providing a strip of binding material, substantially V-shaped in cross-section, in separating the strands to be bound, placing the V-shaped strip between the separated strands, and forming the strands and the upper portions of the V-shaped binder strip inwardly, the folds in the binder strip being formed to curved shape. 85

5. The method of binding the edges of reed fabric and the like that consists in providing a metal strip of binding material substantially V-shaped in cross-section, in separating the strands to be bound, placing the V-shaped strip between the separated strands, and forming the strands and the upper portions of the V-shaped binder strip inwardly. 95

6. The method of binding the edges of reed fabric and the like that consists in providing a metal strip of binding material substantially V-shaped in cross-section, in separating the strands to be bound, placing the V-shaped strip between the separated strands, forming the strands and the upper portions of the V-shaped binder strip inwardly, and then pressing the parts into compact relation. 105

7. The method of binding the edges of reed fabric and the like that consists in providing a metal strip of binding material substantially V-shaped in cross-section, in separating the strands to be bound, placing the V-shaped strip between the separated strands, placing a rod in the bottom of the V-shaped binder strip, and forming the strands and the upper portions of the V-shaped binder strip inwardly. 115

8. The method of binding the edges of reed fabric and the like that consists in providing a metal strip of binding material substantially V-shaped in cross-section, in separating the strands to be bound, placing the V-shaped strip between the separated strands, placing a rod in the bottom 125

of the V-shaped binder strip, forming the strands and the upper portions of the V-shaped binder strip inwardly, removing the rod and then pressing the parts into compact relation.

9. The method of binding the edges of reed fabric and the like that consists in providing a metal strip of binding material substantially V-shaped in cross-section, but 10 with a curved bottom portion, in separating the strands to be bound, placing the V-shaped strip between the separated strands, placing a rod in the bottom of the V-shaped binder strip, and forming the strand and 15 the upper portion of the V-shaped binder strip inwardly.

10. The method of binding the edges of reed fabric and the like that consists in providing a metal strip of binding material, substantially V-shaped in cross-section, in 20 separating the strands to be found, placing the V-shaped strip between the separated strands, placing a rod in the bottom of the V-shaped binder strip, forming the strands and the upper portion of the V-shaped 25 binder strip inwardly, the fold being formed to curved shape, and thereafter removing said rod.

In testimony whereof, I have hereunto set my hand, this 8th day of Sept, 1921.

MARSHALL B. LLOYD.
